(57) **CLAIM**

The ornamental design for a utility pouch, as shown and described.

DESCRIPTION

FIG. 1 is a front elevational view of a utility pouch; FIG. 2 is a top plan view thereof; FIG. 3 is a rear elevational view of FIG. 1; FIG. 4 is a bottom plan view thereof; FIG. 5 is a left-side elevational view of FIG. 1; and, FIG. 6 is a right-side elevational view of FIG. 1. The broken line showing of a zipper pull in FIG. 2 is for illustrative purposes only and forms no part of the claimed design.
